UNITED STATES PATENT OFFICE.

WILLIAM L. MILLER, OF ST. PAUL, MINNESOTA.

RADIO TUNING DEVICE.

Application filed September 2, 1925. Serial No. 54,129.

My invention relates to radio tuning devices and has for an object to provide a device employing a fixed inductance coil and a movable inductance coil with means for micrometrically adjusting the relative coupling of said coils.

Another object of the invention is to provide a rotatable support for said movable coil and to provide means for adjusting the position of said movable coil relative to said support.

A still further object of the invention resides in supporting said movable coil so that the same may be adjustably rotated about two axes lying at right angles to one another.

One of the features of the invention is to provide the movable coil with a shaft on which said coil is fixed for rotation, and to provide a support for said shaft which is itself mounted upon a shaft positioned at right angles to said first named shaft, and to further provide an operating spindle for said first named shaft which passes thru said second shaft.

A feature of the invention resides in attaching to said last named shaft a yoke which supports said first named shaft detachably, whereby the movable coil and shaft attached thereto may be conveniently removed from the device, permitting of interchanging coils.

A still further object resides in providing a one hole mounting for the entire device whereby the fixed coil or the entire structure may be easily and quickly placed in position, or removed.

Another object of the invention is to provide a gear train for operating the first shaft from said spindle whereby said spindle travels at a greater rate of speed than said first named shaft.

Other objects of the invention reside in the detailed construction of the invention as disclosed in the following specifications and drawings and brought out in the claims.

In the drawings illustrating my invention in one form:

Fig. 1 is a plan sectional view of my invention.

Fig. 2 is a sectional view taken on line 2-2 of Fig. 1 with portions of the same omitted.

Fig. 3 is a view similar to Fig. 1 showing a modification of the invention.

Fig. 4 is a view similar to Fig. 2 taken on line 4-4 of Fig. 3.

Fig. 5 is an enlarged sectional view of one form of the operating mechanism of the invention.

Fig. 6 is a view similar to Fig. 1 of another form of the invention.

Fig. 7 is an elevational view taken on line 7-7 of Fig. 6.

Fig. 8 is an enlarged sectional view of the spindle and mount of the invention.

Fig. 9 is a detail view showing the method of attaching a tubular coil to the mounting.

Fig. 10 is a detail view of another form of coil mounting.

In radio receiving apparatus it is highly desirable to have an inductance coil which may be micrometrically adjusted to vary the inductance in the circuit. This is particularly true in regenerative receiving apparatus using a tickler coil especially at low wave lengths where the degree of feed back required to produce the best results is very slight. In such cases it is very desirable to have a tickler coil which may have a sufficient number of turns on it and a correspondingly high value of inductance so that sufficient feed-back may be had for longer wave lengths where a relatively greater amount of feed-back is required for best results.

My invention meets with these requirements in providing an adjusting mechanism which admits of a considerably more delicate adjustment in one position than in its other positions thereby permitting the movable coil to be wound with a sufficient number of turns and of correspondingly high inductance value to meet with the maximum feed-back requirements and at the same time to be most accurately or finely adjusted when in its more loosely coupled positions.

The form of the invention shown in Figs. 1 and 2 is especially adapted to be mounted on a panel and in these figures I have illustrated a portion of a panel in section which is designated at 10. The invention here illustrated is of the nature of a variocoupler A, which consists of a fixed coil 11 and a movable coil 12. The fixed coil 11 may be of the ordinary type being a single layer coil 14 wound on an insulating tube 13. A bracket 15 attached to the tube 13 is bolted to the panel 10 by means of small machine screws 16. Although I specify a single layer or solenoid coil for coil 14 it can be

readily understood that a bank-wound coil or a spider web coil or the ordinary form of basket wound coil or any flat-wound may be used with like effect.

5 Immediately above the winding 14 of the coupler A I provide a hollow shaft 17, which passes thru the panel 10, the bracket 15 and the tube 13 and which is journaled in said bracket 15. Upon the outer end of the same 10 is attached in the usual manner a dial 18, thru which the shaft 17 extends. On the inner end of said shaft is placed a spacer washer 201, which lies adjacent inner surface of the tube 13. Next to this washer is positioned a pair of fiber blocks 19 and 20 which are rectangular in shape and formed with recesses adapted to fit about the shaft 17. The screws 21 and 22 are screwed into these blocks and serve to hold the same clamped 15 to said shaft 17.

15 The movable coil 12 of my invention is shown in the drawings as being in the nature of a spider web or flat-wound coil with the form on which it is made removed. As a 20 part of the form a shaft 23 is employed which is constructed of an insulating material and over which the windings of the coil are placed in the construction thereof. On removal of the remainder of the form the 25 shaft 23 remains embedded in the coil and upon impregnating the coil in a suitable insulating material said shaft becomes securely cemented to the coil proper.

30 Coil 12 is supported as follows: Secured 35 to the blocks 19 and 20 beneath the screws 21 and 22 are two arms 24 and 25, which diverge to form a fork. At the ends of these arms are arranged sockets 26 which fit over metallic caps 27 attached to the ends of the shaft 23 which protrudes beyond the outer 40 periphery of the coil 12. The arms are formed with spring material so that the same frictionally engage the caps 27 and hold the coil 12 detachably mounted upon 45 the support.

45 For operating the coil 12 about the axis formed by the shaft 23, a spindle or shaft 28 is employed which passes thru the hollow shaft 17. This spindle has attached to it at 50 its outer end a knob 29, which lies adjacent the dial 18, by means of which the same may be rotated. At the inner end of the shaft 17 a collar 30 is attached to the spindle 28 which holds the said spindle in proper position. Upon the end of the said spindle is 55 secured a bevel pinion 31 which meshes with a bevel gear 32 secured to the shaft 23 within the coil 12. By rotating the knob 29 the coil 12 may be turned upon the shaft 23 60 independent of its rotation about the shaft 17.

65 In connecting the coil 12 to the circuit the leads from said coil are directly soldered to the caps 27 positioned on the ends of the shaft 23. The arms 24 and 25 being of

metal make electrical contact with the caps 27 and by attaching the terminals of flexible conductors under the heads of screws 21 and 22 the connections of coil 12 may be brought to the panel 10. It will be readily seen that 70 by spreading the arms 24 and 25 apart, the coil 12 may be quickly removed from its support and another coil substituted in its place. In this manner any number of coils 75 may be interchangeably mounted within the support consisting of the arms 24 and 25.

The form of the invention shown in Fig. 3 and in Fig. 4 differs mainly from that shown in Figs. 1 and 2 in that a different type of reduction gearing is employed and so in the arrangement of the supporting arms. Here I employ two arms 33 and 34 which are imbedded in a block of insulating material 25 cast upon the end of the shaft 17. These arms do not diverge like the arms 24 85 and 25 but run substantially parallel and engage the shaft 23 within the interior of the coil 12 as best shown in Fig. 3. The ends of the arms 33 and 34 are split and arranged with forked openings 36 which are 90 adapted to slip over ferrules 37 mounted on the shaft 23 so as to hold said shaft detachably mounted for rotation.

95 Instead of the bevel gears for operating the shaft 23, in this form of the invention I use a worm 38 which is attached to the end of the spindle 28 and meshes with a small worm wheel 39 secured to the shaft 23. This arrangement of course brings the shaft 23 out of the plane of the shaft 17 and the 100 spindle 28. To overcome this the coil 12 is placed with the shaft 23 slightly eccentrically positioned so that the actual center of the coil proper comes substantially at the center of the shaft 17. 105

110 The ratio of the gears for rotating the shaft 23 may be any desired ratio but I have found it most practical to employ a one to three or a one to four ratio. Since the effective angle of rotation of the coil 12 is 110 90 degrees to bring said coil from its position of maximum coupling to its position of minimum coupling a one to four ratio permits of a 360 degree rotation of the knob 29 for the entire range of the movement of 115 the coil 12.

120 The operation of the invention will best be comprehended from an inspection of Figs. 3 and 4. Assume that the coil 12 is to be arranged for a small amount of intercoupling with the coil 11. The said coil would then be set as illustrated with the plane of said coil positioned almost at right angles to the coil 11. Say for example that this coupling was 10% of the maximum. When 125 the coil 12 is placed as shown in full lines in Fig. 3 by rotating the dial 18, the maximum coupling obtainable with the particular setting of the knob 29 is being had. By rotating the dial 18 90 degrees the coil 12 will 130

take the position shown in dotted lines in Fig. 3 at which position the minimum coupling is being had. It can therefore be readily seen that with a 90 degree rotation 5 of the dial only 10% of the entire range may be covered hence making the adjustment at loose coupling more refined and precise than with the ordinary form of coupler where the entire range is covered in a 90 degree rotation of the dial. When the maximum feed-back of the coil 12 as procured by the knob 29 is very slight it can be readily seen that the adjustment procured by the rotation of the dial 18 is almost micrometric. 10 On the other hand when the coils 12 and 11 are set so that the coupling between them is secured by the adjustment of the knob 29 approaches the maximum which takes place when the coils are closest to being parallel. 15 Then the adjustment had by rotating the dial 18 is much coarser than may be had by the rotation of the knob 29 alone. Such adjustment then is practically the same as in the ordinary form of variocoupler. This arrangement meets with all the requirements of feed-back as a proper adjustment is had at all wave lengths. 20 In Fig. 5 I have shown another method of attaching the arms of my invention to the shaft 17 thereof. The end of shaft 17 is threaded for a distance along the same as indicated at 40. Upon this threaded portion are placed two nuts 41 and 42 between which the two arms 43 and 44 are clamped. 25 Said arms are kept electrically insulated from each other by means of washers 45 and 46 which are made of fiber and which separate said arms from one another and from the shaft 17. In this manner the current feeding the coil 12 may be conducted thru the arms 43 and 44 as desired. 30 For providing the necessary friction between the various rotating parts crow foot springs 47 and 48 may be employed which 35 may be inserted between the knob 29 and the dial 18, and between the dial 18 and the panel 10. In Fig. 5 is shown another method of producing the desired friction between the knob 29 and the dial 18. Here the interior of the shaft 17 is enlarged at 49 to receive a compression coil spring 50 which bears against a shoulder 51 formed in the shaft 17 and also against the collar 30 secured to the spindle 28. 40 In Figs. 6, 7 and 8 I have shown a form of the invention which most nearly resembles that disclosed in Figs. 1 and 2. The principal difference, however, resides in the substitution of a flat coil for the tubular coil 45 and mounting it from a single support. Also the leads to the movable coil have been taken directly from the same instead of thru the supporting arms. 50 In this form of the invention the hollow shaft 17 is journaled in a flanged bushing 60 which is threaded upon its exterior at 61 and clamped upon the panel 10 by means of a nut 62. A collar 63 is pressed upon said shaft in spaced relation to the bushing 61, between which and a washer 64 a compression coil spring 65 is positioned which serves to hold the dial 18 in frictional engagement with the bushing 60, thereby eliminating the spring 48. The end of the shaft 17 has secured to it a yoke 66 formed with arms 67 and 68 which take the place of arms 24 and 25, these arms being similarly constructed to the arms 33 and 34 of the form of the invention shown in Figs. 3 and 4. By employing a metallic shaft 69 instead of the shaft 23 the grooved portions 26 of the arms 67 and 68 directly engage said shaft, thereby eliminating the ferrules 37. Upon the ends of the shaft 69 are attached clips 70 by means of which the coil 12 may be readily attached thereto. The gear 32 is attached to shaft 69 and meshes with the gear 31 which is mounted on the end of the spindle 28. 60 As previously stated the form of the invention shown in Figs. 6, 7 and 8 permits of supporting both coils thru a single-hole mount. In these figures I have shown a flat coil 71 as the fixed coil which is supported as follows: An arcuate plate 72 of insulating material such as fiber is positioned adjacent the coil 71, said coil being held attached thereto by means of two fiber bands 73 which pass around said coil and are attached to the plate 72 by means of bolts 74 and 75 which may form the binding posts 100 of the coil if desired. A metal angle 76 is riveted to the plate 72 and is formed with an open ended slot 77 by means of which the same may be held in place upon the bushing 60 between the panel 10 and the nut 62, which may be tightened against it. When it is desired to exchange or remove the fixed coil, the result is easily accomplished by loosening the nut 62 and sliding the entire coil unit out. 110 The mounting shown in Figs. 6 and 7 may also be used in supporting a tubular or solenoid coil. For this purpose an attaching member 78 is used which is arranged with the slot 77 and which has two arms 79 and 80 bent outwardly therefrom at right angles thereto. These arms are formed arcuate at their ends 81 where they fit along the periphery of the coil proper so that the same may be riveted or bolted thereto. 115 The coil 71 shown in Fig. 7 may be formed with two or more separate windings arranged in fixed relation to one another and wound to form part of the same coil, providing a primary and a secondary. If desired the primary and secondary may be made separate, one of them being supported on a supporting angle 76, the same as illustrated in Fig. 7, while the other could be supported on a device such as shown in Fig. 120 130

10. This structure consists of a plate 86 adapted to be clamped along with the angle 76 beneath the nut 62. A forked portion 87 is hingedly connected at 88 to the plate 86 and carries the coil proper in the same manner as angle 76 illustrated in Fig. 7. With this arrangement, the coil so supported can be arranged in any inductive relation to the fixed coil and the movable coil giving a wide latitude in adjustment of the relative inductive coupling of the coils.

Altho I have described my invention primarily as adapted to a varicoupler yet it can be readily understood that the same may be used as a variometer or as any other tuning device employing a pair of coils between which the coupling may be altered at will. The method of using and connecting up tuning devices of the nature of my invention being so well understood in the art I have not deemed it necessary to show wiring diagrams therefor or to otherwise describe the same in detail.

25. The invention may be used as a variable inductance, not only in the form of a varicoupler, but also as a variometer by conductively connecting the fixed and movable coils in the usual manner, said coils being provided in suitable inductance values for any given tuning circuit. It may also be utilized as a radio frequency transformer, or tuning unit, by utilizing the movable coil as the primary and the fixed coil as the secondary, or vice-versa, said coils being provided of desired inductance value for any given circuit.

40. In any circuit, receiving or transmitting, my invention is adaptable by reason of its mechanical features to numerous variable uses because of the fine adjustments possible between the fixed and movable coils.

45. The principal advantage of my invention resides in that the coupling between the movable and fixed coils of my invention may be accurately adjusted over the entire band of wave lengths so that the signals may be picked up with greater ease and so that a greater number of stations may be tuned in where employed in any given receiving circuit. The invention is exceedingly simple and is easily operated, there being a minimum number of parts to get out of order. The two controls for the operation 50 of the device being concentrically mounted so as to be readily accessible and conveniently manipulated.

Having described my invention in the form which I consider the best embodiment thereof, I desire to have it understood that the invention may be constructed in different forms and put to different uses within the scope of the following claims:

Claims—

65. 1. A radio tuning device for application

to a fixed support comprising a coil mounted upon said support, a second coil arranged for rotation relative to said first coil about two intersecting axes, an operating member having a fixed situs relative to said support 70 for rotating said movable coil about one of its axes, and another operating member having a fixed situs relative to said support for independently rotating said coil about its other axis. 75

2. A tuning device comprising a fixed coil, a hollow shaft rotatably mounted relative to said fixed coil a support carried by said shaft, a second shaft angularly disposed relative to said first shaft and journaled in 80 said support, a coil carried by said second shaft, a spindle passing through said first shaft and operating means connecting said spindle and second shaft for independently rotating said second shaft. 85

3. A tuning device comprising a bushing, a hollow shaft rotatable therein, a coil mounted on said shaft, for rotation relative thereto, a spindle passing through said shaft for rotating said coil, an abutment on said 90 hollow shaft engaging said bushing on one side, said spindle being frictionally restrained from free movement, a collar on said hollow shaft on the side opposite said abutment and spaced from said bushing, and 95 a coil spring surrounding said hollow shaft and seated between said bushing and collar for creating a frictional resistance to said shaft in excess of that of said spindle.

4. A tuning device comprising a fixed coil, 100 a shaft rotatably mounted relative to said fixed coil, a support carried by said shaft, a second shaft mounted in said support, being positioned at right angles to said first named shaft, means for rotating said second 105 shaft extending thru said first named shaft and a movable coil mounted upon said second shaft.

5. A tuning device comprising a fixed coil, a hollow shaft rotatably mounted relative to 110 said fixed coil, insulating means attached to the end of said hollow shaft, a pair of arms secured to said insulating means, a shaft rotatably mounted at the ends of said arms at right angles to said hollow shaft, a spindle 115 passing thru said hollow shaft and rotatable therein, a gear on the end of said spindle, a second gear on said second shaft meshing with said first gear, and a movable coil mounted on said second named shaft. 120

6. A tuning device comprising a flanged bushing, a nut screwable thereon, a shaft rotatable within said bushing, a coil mounted on said shaft, an angle plate removably attached to said bushing, and a coil secured 125 to said angle plate.

7. In combination with a panel a coil mounting comprising a bushing adapted to pass therethrough, a nut screwable upon the end of said bushing, an angle plate having 130

an open ended slot adapted to pass over said bushing and a coil secured thereto.

8. In combination with a panel a coil mounting comprising a bushing adapted to pass therethrough, a nut screwable upon the end of said bushing, an angle plate having an open ended slot adapted to pass over said bushing, an arcuate insulating plate attached to said angle, a coil lying adjacent 10 said plate and a pair of bands passing around said coil and secured to said plate for holding the coil attached thereto.

9. A tuning device comprising a fixed coil, a shaft rotatably mounted relative to said 15 fixed coil, a support upon the end of said shaft comprising a pair of spaced arms, a second shaft, a coil mounted upon said second shaft, and means formed on the end of said arms for detachably supporting said 20 second shaft for rotation relative to said first shaft.

10. A tuning device comprising a fixed coil, a shaft rotatably mounted relative to said fixed coil, a support upon the end of said shaft comprising a pair of spaced arms, 25 said shaft

a second shaft, a coil mounted upon said second shaft, and releasable operating means for rotating said second shaft relative to said first shaft.

11. A tuning device comprising a fixed 30 coil, a shaft rotatably mounted relative to said fixed coil, a support upon the end of said shaft comprising a pair of spaced arms, a second shaft, a coil mounted upon said second shaft, said arms having resilient 35 curved fingers formed on the ends thereof adapted to surround said second shaft for detachably holding the same in place.

12. A tuning device comprising a fixed planiform coil having a central opening, a 40 shaft lying along said coil, a support attached to the end of said shaft, a second shaft angularly situated relative to said first shaft and journaled in said support, and a second coil attached to said second shaft, 45 said second shaft, coil and support being revolvable within the opening in said first coil.

In testimony whereof I affix my signature.
WILLIAM L. MILLER.
